UNITED STATES PATENT OFFICE.

FRANCIS L. PRUYN, OF NEW YORK, N. Y.

APPARATUS FOR SETTING PILES.

1,275,470.

Specification of Letters Patent. Patented Aug. 13, 1918.

Application filed August 5, 1913. Serial No. 783,062.

To all whom it may concern:

Be it known that I, FRANCIS L. PRUYN, a citizen of the United States, residing at New York, in the county and State of New York, have invented certain new and useful Improvements in Apparatus for Setting Piles, of which the following is a specification.

My invention relates, more particularly, to the setting in the ground of prepared concrete piles, the method of which consists in penetrating the ground with a driver to make a hole, the driver being accompanied in its downward movement by an outside shell or envelop to hold the ground; then withdrawing the driver and introducing into the outside shell a pre-molded pile, and, finally, in withdrawing the outside shell, preferably, in sections.

In the accompanying drawings, Figure 1 is a central longitudinal section of one form of my device in driving position. Fig. 2 shows the driver removed and a premolded pile inserted in its place. Fig. 3 shows a filling of grout between the prepared pile and the outside shell or envelop. Fig. 4 is in part a section and in part an elevation of the finished pile. Fig. 5 is a modification of Fig. 1. Fig. 6 is the modified device after the driver has been removed and a prepared pile inserted and resting upon grout previously deposited in the driving point. Fig. 7 shows the same after grout has been inserted to fill the space between the pile and the outside shell. Fig. 8 shows the completed pile resting upon the driving point after the outside shell has been removed. Fig. 9 is a top plan view of the driver and outside shell.

Referring to the drawings in detail, A is the outside shell, or envelop, which, as heretofore explained, is used to hold the ground as the driver proceeds downwardly and also after the latter is withdrawn. Preferably, it is made in longitudinal sections, as shown in Fig. 9, with longitudinal flanges A' A'' which are riveted to or made integral with the outside shell. B indicates the driver, the stem of which B' for lightness and convenience in handling, is shown as a tube, although it may be made solid. In the stem are grooves B'' into which the flanges of the outside shell are set for the purpose of binding the sections of the latter firmly together.

A thrust-plate B' is welded or otherwise

securely attached to the inside of the stem near its lower end, having a depending portion B' extending to the end of the stem, for strengthening the latter, while the portion above is reinforced by reinforcing plates B''. The driver B is provided with a driving-point C, which has a reduced portion C' fitting into the thrust-plate, and a shoulder C'', upon which to rest the end of the stem B', the depending portion of the thrust-plate B' and the end of the outside shell. The position in the stem of the thrust-plate, besides making a socket for the head of the driving-point for holding the latter to its work, adds great strength to the lower portion of the stem.

In the present instance I have shown the driving-point C made of a metallic shell filled with concrete, but it may be made entirely of concrete, or it may be entirely metallic.

Upon the upper portion of the driver and overlapping the outer shell I have shown a driving-cap D, which may be constructed in any suitable manner, for the purpose of receiving the impact of the driving weight.

The method herein shown and described has several advantages over former methods. When the work is done with a single tube, as heretofore, it must be depended upon not only to drive, but to hold the ground as well; and it cannot be removed until the pile is set. Consequently, such a driving tube cannot be reinforced to correct its tendency to buckle, as struts or braces would interfere with the placing of the piles. Moreover, to be able to withdraw, in longitudinal sections, the tube used to hold the ground, is an advantage, as the friction of the ground against it is so great, at times, that it is nearly if not quite impossible to withdraw it as a whole.

Referring to Figs. 2, 3 and 4, E is a pre-molded concrete pile inserted within the outer shell after the driver has been withdrawn. E' E'' indicate a filling of grout between the pre-molded pile and the outer shell.

In Fig. 5 the stem is made conical, and the metal driving-point is made hollow with an annular flange C' for receiving the end of the outer shell, while the end of the stem B' rests in the lower portion of the driving-point.

In Fig. 6 E indicates a pre-molded con-

crete pile which has been inserted in the outer shell after the removal of the driver, some of the plastic concrete which had previously been introduced inside the driving-point being raised between the pile and the wall of the outer shell.

In Fig. 7 E' E' indicates the plastic concrete filling the space between the outer shell and the pre-molded pile. The completed 10 conical pile is shown in Fig. 8, resting in the driving-point, the outer shell removed. One advantage of the conical form is that the sections of the outer casing are more readily removed from the ground, owing to 15 the fact that as soon as the removal of the tapered section is started the contact of the ground diminishes along its entire length.

What I claim is:

1. The combination with a driving member 20 of a surrounding shell having a plurality of longitudinal sections, holding means extending along the edges of said sections and means extending longitudinally of the driving member and coöperating with the holding means on the sections for releasably holding the sections together.

2. The combination of a driving member and a surrounding shell, the latter having a plurality of longitudinal sections, flanges 30 extending along the edges of the sections, said driving member having grooves for holding said flanges and thereby preventing displacement of the sections.

3. The combination with a driving-tube 35 of a surrounding shell having a plurality of longitudinal sections, means extending along the edges of said sections, and means extending longitudinally of said driving-tube and coöperating with the means along

the edges of the sections for releasably holding the sections together. 40

4. The combination with a driving-tube of a surrounding shell having longitudinal sections and flanges extending along the edges thereof, said tube having grooves into 45 which said flanges are set to bind the sections together.

5. The combination with a driving head 50 of a driver and a surrounding shell having a plurality of longitudinal sections, interlocking means consisting of flanges extending along the edges of said sections and grooves extending longitudinally of the driver into which said flanges are set and which coöperate with the head to prevent 55 displacement of the sections.

6. In a device of the class described, the combination of a driving-point, a driving-tube having a thrust-plate in its lower end with a depending portion adapted to prevent buckling of the lower end of the tube and to drive the point, and a surrounding shell having a plurality of longitudinal sections, means extending along the edges of 60 said sections, and means extending longitudinally of said driving tube and coöperating with the means along the edges of the sections for releasably holding the sections together. 65

In witness whereof I have hereunto set my hand, in the presence of two subscribing witnesses, at New York, in the county and State of New York, this 19th day of July, 1913.

FRANCIS L. PRUYN.

In presence of—

RALPH JULIAN SACHERS,
BERTHA M. KELLY.
